SPECIFICATION forming part of Design No. 18,587, dated September 4, 1888.

Application filed May 28, 1888. Serial No. 275,401. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying drawing, forming a part thereof.

10 The name of the group is "The First Ride," which is stamped on the base. A farmer stands by the head of his horse, with the reins passing through his left hand and with his right supporting a small boy, who is sitting astride 15 the horse and holding the end of the reins. The child's mother stands on the right hand

side of the horse and holds him on. She has a hat with feathers on her head and a shawl over her shoulders. The head of the horse is near the ground, nibbling some leaves.
